[57] CLAIM

The ornamental design for an electronic ozonation unit,
as shown and described.

DESCRIPTION

FIG. 1 is a front, side and top perspective view of an
electronic ozonation unit showing my new design;
FIG. 2 is a side elevational view thereof, the opposite
side being a mirror image of that shown;

FIG. 3 is a front elevational view thereof;

FIG. 4 is a rear elevational view thereof;

FIG. 5 is a top plan view thereof; and,

FIG. 6 is a bottom plan view thereof.

FIG. 1

FIG. 2
